UNITED STATES PATENT OFFICE.

LEWIS F. ELKINS, OF PONTIAC, MICHIGAN.

DIE FOR SPRING-FORMING MACHINES.

1,331,630.

Specification of Letters Patent. Patented Feb. 24, 1920.

Application filed June 18, 1919. Serial No. 305,151.

To all whom it may concern:

Be it known that I, LEWIS F. ELKINS, citizen of the United States, residing at Pontiac, county of Oakland, State of Michigan, have invented a certain new and useful Improvement in Dies for Spring-Forming Machines, and declare the following to be a full, clear, and exact description of the same, such as will enable others skilled in the art to which it pertains to make and use the same, reference being had to the accompanying drawings, which form a part of this specification.

My invention relates to the dies of spring forming machines, shown in the accompanying drawings and more particularly described in the following specification and claims:

Heretofore it has been customary to construct spring forming and tempering machines with dies which were not adapted to be removed from the machine,—it being necessary to "make up" the forming dies for each job and when repeat orders were received, it became necessary to reassemble the several parts of the die before the work could be again undertaken.

That the several leaves of a spring should exactly conform to the shape of the adjacent leaf in order to secure proper spring action is well understood in this art;—therefore, in order to obtain this result the greatest care must be exercised in making up the "forms" for the leaves of a spring—35 the work requiring the services of a skilled mechanic.

It will be obvious therefore that the time and labor necessary to "fit" up the dies for duplicate orders of the respective leaves is thus lost and that it is exceedingly difficult, if not impossible, to reassemble the parts of the die so they will produce the exact duplicate of the shape of a prior output.

It is therefore one of the objects of the present invention to provide co-acting pairs of dies constructed with adjustable fingers, that any desired form may be given to the spring leaf, the co-acting pairs of the die being adapted for installation on any of the standard spring forming machines;—the arrangement being such that the dies may be removed from the machine upon the completion of an "order" and stored away for future use without disturbing the respec-

tive elements of the die that the leaves of 55 a spring may be exactly duplicated at any time,—thereby standardizing the leaves without the loss of time necessary for reassembling the component parts of the die.

A further object of the invention is that 60 the dies may be "made up" while the machine is in use,—thus avoiding tying up the operation of an expensive and productive machine.

With the foregoing and other objects in 65 view which will appear as the description proceeds, the invention resides in the combination and arrangement of parts and in the details of construction hereinafter described and claimed, it being understood 70 that changes may be made in the precise embodiment of the invention herein disclosed without departing from the spirit of the same.

In the accompanying drawings:— 75

Fig. 1 is a plan view of a spring forming machine, showing the co-acting members of the die secured thereto, with a spring blank in position to be operated upon.

Fig. 2 is a similar view of a portion of 80 the die showing the co-acting members of the latter in "closed" position to form the blank.

Fig. 3 is a cross-sectional view on line 3—3 of Fig. 1. 85

Fig. 4 is a cross-sectional view on line 4—4 of Fig. 1.

Fig. 5 is an end elevation of a spring forming machine with the dies mounted thereon.

Fig. 6 is a cross-sectional view on line 6—6 of Fig. 1—showing the movable member of the die in its initial or "open" position.

Fig. 7 is a similar view with the movable 95 member of the die in "closed" position,—as when acting upon the spring blank.

Referring now to the letters of reference placed upon the drawings:—

A, and P, are co-acting die frames conforming to the general shape of the spring to be manufactured. The frame A, is secured by bolts B, to a stationary member C, of the spring forming machine D.

E, indicates a plurality of adjustable 105 blocks located in abutting relation to each other having projecting ribs E', adapted to bear against the spring blank Z. Extending

from the rear of the blocks E, into corresponding recesses in one of the side walls A', of the frame, are rectangular lugs E², to secure the blocks from rotating upon their own axis. F, are bolts bridging the spaced side walls of the frame A, on one end of which are secured the blocks E. F' and F², are nuts for securing the bolts when adjusted.

10 The movable die frame P, is bolted at Q, to a reciprocating member R, of the spring forming machine.

The general shape of the movable frame P, is complementary to the stationary die frame A. S, indicates a plurality of adjustable blocks,—having ribs E', and lugs E²,—similar in form to the blocks E,—against which they are arranged in opposing relation.

20 T, are bolts for supporting the blocks S, in the frame P, fitted with nuts T', for adjusting the blocks. U, denote springs sleeved upon the bolts with one end bearing against the nuts T, and the other end against 25 the wall of the frame P, the purpose of which is to provide for a slight yieldable relation between the spring gripping blocks E, and S,—that the spring blank may expand and contract between the same.

30 V, indicates a suitable toggle lever mechanism adapted to be actuated by a manually operated lever W, for forcing the movable member R, with its die P, toward and away from the die A, for forming the spring.

35 It will be seen that dies adapted to form the several leaves of a vehicle spring may be made up to conform with the adjacent leaf of the spring and that upon the completion of the required number of "leaves,"

40 the dies may be removed and another set of dies installed without holding up the operation of the machine longer than is necessary to make this change. The dies upon removal from the machine may be stored

45 for future use without disturbing the adjustment of any of its parts;—thus exact duplicates of the spring may be made at any time without the loss of time necessary for "making up" a die for each occasion.

Having thus described my invention, what I claim is:—

1. In a spring machine, a self contained removable spring forming die comprising a pair of coördinating frames having spaced side walls, a plurality of bolts bridging the opening between the side walls of the frames, a plurality of blocks secured to the end of the bolts, means for securing each block against turning upon its axis, means for adjusting said blocks, means for securing the blocks of one frame when adjusted, means for providing a yieldable action of the blocks of the opposing frame when gripping a spring blank, and means for detachably securing said coördinating frames in a spring machine, whereby the die frames may be removed for future use without danger of displacing the several parts of said die.

2. In a spring machine, a self contained removable spring forming die comprising a pair of coördinating frames having spaced side walls, a plurality of bolts bridging the opening between the side walls of the frames, a plurality of blocks secured to the ends of the bolts, having projecting ribs adapted to bear against a spring blank, said blocks each having a rectangular lug fitted to a corresponding recess in the wall of the frame, whereby each block is held against turning upon its axis, nuts mounted upon said bolts for adjusting said blocks, means for securing the blocks of one frame when adjusted, means for providing a yieldable action of the blocks of the opposing frame when gripping a spring blank, and means for detachably securing said coördinating frames in a spring machine, whereby the die frames may be removed for future use without danger of displacing the several parts of the die.

In testimony whereof, I sign this specification in the presence of two witnesses.

LEWIS F. ELKINS.
